UNITED STATES PATENT OFFICE.

DWIGHT W. HUSTON, OF SPRINGFIELD, OHIO, ASSIGNOR TO WAYNE TANK & PUMP COMPANY, OF FORT WAYNE, INDIANA, A CORPORATION OF INDIANA.

ILLUMINATING SIGN FOR GASOLINE PUMPS.

Application filed February 15, 1924, Serial No. 693,043. Renewed December 6, 1924.

To all whom it may concern:

Be it known that DWIGHT W. HUSTON, a citizen of the United States of America, residing at Springfield, in the county of Clark 5 and State of Ohio, has invented new and useful Improvements in Illuminating Signs for Gasoline Pumps, of which the following is a specification.

The purpose of the present invention is to 10 provide, in an illuminating sign for gasoline pumps or similar articles, an all metal construction including a sign plate or panel having signs on both faces and a casing for the sign plate or panel provided with inner 15 reflecting surfaces so disposed as to reflect the light rays from a single electric lamp upon both faces of the sign plate or panel, rendering the signs brilliantly illuminated.

Another purpose is to provide an electric 20 lamp at the base of the casing where it connects to the top of the gasoline pump, the sign plate or panel being mounted in the casing in order to bisect the light rays which are reflected by the walls of the casing toward and upon the opposite faces of the 25 sign plate or panel, hence more brilliantly displaying the signs.

Still another purpose is to provide a casing 30 with opposed parts, the adjacent edges of which are interlocked and provided with means for holding the marginal edge of the sign plate or panel in position intermediate the remote edges of the opposed parts, which parts have their walls converged from the 35 opposite faces of the plate or panel, whereby the light rays from the single lamp at the lower edge of the plate or panel are reflected toward and upon the opposite faces of the plate or panel.

40 A further purpose is the provision of reflectors struck up from opposite sides of the base of the casing for the purpose of reflecting the light rays from the single lamp outwardly and downwardly exteriorly of the 45 casing and upon the gauges, etc., of the gasoline pump, thereby brilliantly illuminating these parts in order to facilitate the operator's attention to the pump.

It is to be understood that the particulars 50 herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a view in perspective of the 60 improved illuminating sign constructed in accordance with the invention.

Figure 2 is a vertical sectional view through the same on line 2—2 of Figure 1. 65 Figure 3 is an enlarged detail view of a portion of the casing showing the manner of holding the sign panel or plate between the two parts of the casing.

Figure 4 is a sectional view through a modified form of illuminating sign for gaso- 70 line pumps.

Referring to the drawings, 1 designates the base or pedestal of the casing which is of conical contour and 2 designates the upper circular part of the casing. The base 75 or pedestal fits in any suitable manner, as at 3, on the top of the casing of a gasoline pump. The top of the gasoline pump is equipped with a suitable fixture 4 provided with a socket (not shown) for the reception 80 of a single electric lamp or bulb 5.

The upper circular portion of the casing is formed in two parts constituting reflector 85 rims and, as shown, these rims converge in opposite directions from opposite sides of a sign plate or panel 6. The adjacent edges of the two rims 7 and 8 of the casing are provided with interlocking connections, such as a flange 9 on the edge of the rim 8 and an overhanging flange 10 on the part 90 7. The overhanging flange is circular in cross section and overlies the flange 9. Due to the flange 10 being circular, a channel 11 is formed for the reception of the marginal edge of the plate or panel 6, thereby 95 supporting the plate or panel securely in position.

The casing may be constructed of any suitable metal, preferably sheet metal of relatively heavy gauge, while the sign plate or panel may be constructed of similar material, although other material may be used, for instance, such as glass or the like.

100 It is the purpose to apply signs upon opposite faces of the plate or panel 6, such as the word "Gasoline." Any type of lettering may be used in applying the sign. The lettering may be in white with a dark background so that the letters of the sign are clearly visible and very brilliant due to the 105 110

light rays being reflected thereon. However, it is obvious that a heavy dark lettering may be employed with a light background. It is also obvious that the signs 5 may be applied in any other way.

The rims 7 and 8 of the casing are converged for the purpose of reflecting the light rays, as indicated by dotted lines, toward and upon the opposite faces of the 10 plate or panel. In order to reflect brilliant light rays and to render the signs bright, it is the purpose to construct the opposed parts of the casing of relatively heavy sheet metal finished throughout with porcelain 15 enamel, preferably white.

Opposed parts of the base or pedestal of the casing are provided with struck up reflectors 12 which are inclined outwardly and downwardly and their inner faces are likewise 20 enameled white for the purpose of reflecting the light rays from the single lamp in opposite directions downwardly and exteriorly of the base or pedestal and toward and upon the various gauges, etc., of the 25 gasoline pump, thus rendering these parts more visible to the operator at night.

As shown in Figure 4, it is obvious that the remote edges of the top rims of the casing may support glass panels or covers 14 30 for the purpose of protecting the sign as well as protecting the lamp in the base or pedestal of the casing. In order to hold the glass panels or covers in place, the remote edges have channels. 13.

35 An illuminating sign of this character is practically indestructible and presents a nice appearance and brilliant at night, diffusing sufficient light rays to illuminate the surroundings as well as rendering the signs 40 on both faces of the panel or plate clearly visible.

Heretofore there have been devised illuminating means having upwardly curving surfaces which catch the direct rays from the light but in this construction there is no reflection. It will be noted that the present invention specifies a flat surface provided 45 with signs on both sides which are illuminated by reflection of the light rays from a single lamp through the medium of a reflector-retainer element consisting of the two rims 7 and 8 disposed at angles. The present invention does not claim a direct 50 illumination from the lamp upon the surface to be made brighter but it is the aim to provide an evenly illuminated sign by the use of the particular character of reflector rim.

55 The invention having been set forth, what is claimed is:

1. An illuminating gasoline pump sign comprising a pedestal adapted for attachment on the top of a gasoline pump, a circular casing rising from the pedestal and provided with a concentrically located sign

panel, the walls of the casing converging toward remote ends of the axis through the center of the panel and provided with inner brilliant surfaces for reflecting light rays toward and upon the opposite faces of the 70 panel which are provided with signs, and illuminating means in the pedestal, the light rays from which are bisected by the sign panel.

2. An illuminating sign including a 75 pedestal with a single electric lamp therein and adapted for attachment to the top of a gasoline pump, a circular casing rising from the pedestal, and a sign panel supported in the casing substantially midway the remote edges thereof and bisecting the light rays, the wall of the casing converging from the opposite sides of the sign panel toward the remote ends of an axis passing through the center of the panel, whereby the inner surface of the casing may reflect the light rays from the single lamp toward and upon the opposite faces of the 80 panel.

2. An illuminating sign including a 85 pedestal with a single electric lamp therein, a circular casing rising from the pedestal, a sign panel supported concentrically within the casing at a position substantially midway the remote edges of the casing, and means for supporting the sign panel in said position, the inner surface of the casing being brilliantly covered and converging from opposite sides of the panel toward remote ends of an axis through the center of the panel, thereby reflecting the light rays from the single lamp toward and upon the 90 opposite faces of the panel.

3. An illuminating sign including a 95 pedestal with a single electric lamp therein, a circular casing rising from the pedestal, a sign panel supported concentrically within the casing at a position substantially midway the remote edges of the casing, and means for supporting the sign panel in said position, the inner surface of the casing being brilliantly covered and converging from opposite sides of the panel toward remote ends of an axis through the center of the panel, thereby reflecting the light rays from the single lamp toward and upon the 100 opposite faces of the panel.

4. An illuminating sign for gasoline 105 pumps comprising a pedestal with a single electric lamp therein, a sign panel rising from the pedestal provided with signs upon opposite faces thereof, and means for reflecting the light rays upon the opposite faces of the panel, the base of the pedestal having opposite downwardly and outwardly disposed reflectors for reflecting the light rays upon various parts of the gasoline 110 pump.

5. An illuminating sign for gasoline 115 pumps comprising a pedestal including a single electric lamp therein, a sign panel rising from the pedestal and provided with signs upon the opposite faces thereof, and a casing on the pedestal, said casing comprising opposed parts provided with interengaging clincher flanges on their adjacent edges, one of said clincher flanges having a channel for the reception of the other flange and for the reception of the marginal edge of the sign panel, thereby holding the panel securely in position.

6. An attachment for a gasoline pump comprising two conical rim sections joined together at their bases and whose inner 120

- surfaces are reflectors, a sign panel mounted between said sections, a pedestal connecting said rim sections with the top of the pump, illuminating means positioned 5 within said attachment and below said sign panel, so that a part of its rays are directed to all sides of the sign, and other reflectors adjacent said illuminating means and so positioned as to direct other rays of said 10 illuminating means to portions of the pump on which said attachment is mounted.
7. An attachment for a gasoline pump comprising a member consisting of two conical rim sections whose inner surfaces 15 are reflectors joined at their bases with a sign panel secured between said sections and a base, the whole of said member adapted to be mounted through its base to the top of a pump, an illuminating element so 20 mounted within said member as to cast part of its rays against the inner surfaces of said conical rim sections so as to be reflected therefrom onto all parts of both sides of said sign panel, and other reflectors so 25 mounted as to direct other rays of said illuminating element toward portions of said pump.
8. An attachment for a gasoline pump comprising a casing formed of two conical 30 rim elements whose inner surfaces are re-
- flectors secured together at their bases and having a base by which said casing is attached to the pump, a sign panel secured between said rim elements within said casing, an illuminating element mounted with 35 in said casing and so positioned that upwardly projected rays therefrom will illuminate both sides of said sign panel, and other reflectors adapted to direct other rays toward the pump on which said attachment is 40 mounted.
9. An attachment for a gasoline pump comprising a casing formed of two conical rim elements whose inner surfaces are reflectors secured together at their bases and 45 having a base by which said casing is attached to the pump, a sign panel mounted concentrically of said rim elements, an illuminating element within said casing so positioned as to direct a portion of its rays 50 upon the inner surfaces of said conical rims and thence upon both sides of said sign panel and other reflectors struck from said casing and positioned adjacent said illuminating element and adapted to direct part 55 of the rays thereof to the pump on which said attachment is mounted.

In testimony whereof he affixes his signature.

DWIGHT W. HUSTON.
